UNITED STATES PATENT OFFICE.

AAGE GEORG PETER WIINGAARD, OF COPENHAGEN, DENMARK.

SAVINGS-CLOCK.

1,338,543.

Specification of Letters Patent. Patented Apr. 27, 1920.

Application filed June 30, 1917. Serial No. 177,894.

To all whom it may concern:

Be it known that I, AAGE GEORG PETER WIINGAARD, a subject of the King of Denmark, and a resident of Copenhagen, Denmark, No. 3 Norrevold, insurance broker, have invented new and useful Improvements 5 in Savings-Clocks, of which the following is a specification.

This invention relates to a savings clock, 10 i. e. a clock connected with a savings-box, and arranged in such manner that the clock stops after the expiration of a fixed time, unless a coin is introduced into a coin chute, which is so connected with the clock work 15 that a device applied in the coin chute acts upon the clock work.

In order to remind the owner of the savings clock, that the time for inserting another coin has come, means are provided so 20 that the dial, some time before the clock stops, is hidden by a cover on which is an inscription corresponding to the purpose. The moving parts of this cover are mechanically so connected with the other parts of 25 the clock work that the cover being in closed position and no fresh coin being inserted, the cover will after a short time return to normal open position and the clock will again run for another period, but after a 30 certain period the cover will again hide the dial and the clock be stopped so that the dial only becomes visible when the owner has again inserted a coin into the coin chute.

It is to be noted that the mechanical arrangements which cover and uncover the clock dial may take a number of forms, and that which will hereafter be described may be regarded only as one example.

The invention is shown in the accompanying drawings in which:—

Figure 1 is an elevation of the clock as seen from the back; all the parts unnecessary for the understanding of the invention being omitted, for instance, the clockwork proper with its appurtenant wheels, springs, winding keys and so forth as well as the clock casing and the coin receptacle.

Fig. 2 is a similar view, but with the plates which are adapted to cover the clock dial in the closed position.

Fig. 3 is a side view of the most important parts of the mechanism, and

Fig. 4 is an elevation showing the cover plates and their moving members in the normal open position.

Fig. 5 is a detail view of the disk which controls the moving members, and

Fig. 6 is a detail view of the holding hook for the cover plates.

Fig. 7 shows a modified form of the cover 60 plate, and

Fig. 8 shows another modification of the cover plate.

Referring to the drawings in detail, 1 is the back plate of the clockwork in which 65 bearings are formed for the gear spindles for the various mechanisms.

The balance 2 of the clockwork co-operates with a stop 3 on an arm 4, which is rotatable upon a pivot 5. The stop is under 70 the tension of a small spring 6. The coin chute 7 has two notches 8 and 9 in which are adapted to enter the bent ends 10 and 11 of a three-armed lever, the arms of which are indicated 12, 13 and 14. This lever is 75 rotatable upon a spindle 15, and the arms 12 and 14 are adjusted in such a manner that the bent end of the one arm will extend into the coin chute, while that of the other arm is outside of the chute.

The free end 16 of the arm 13 so co-operates with a finger 17 on the arm 4 that a turning movement of the lever 12, 13, 14 to the one side will lift the stop 3 from the balance 2, while a turning movement to the 85 opposite side will lower it down against the stop.

The end of the arm 14 has a hook-shaped bend 18 (Figs. 3 and 4) which co-operates with a radial notch 19 in the disk 20 (Fig. 90 5) which together with a gear wheel 21 is mounted upon the spindle 22. The notch 19 is normally covered by a plate 23 rotatable upon the pin 22, which plate is kept in place by a spring 24. The plate 95 23 is of a length approximately the diameter of the disk 20.

The clock dial may be covered by two plates 25 and 26, which are rotatable on the pins 27 and 28 in the frame parts 29 and 100 30 of the frame. The two covering plates have fixed crank arms 31 and 32, of which the arm 31 is connected by a link 33 with the one arm of the three-armed lever 34, 35, 38, the other arm of which is connected 105 by a link 36 with the crank arm 32.

The lever 34, 35, 38 is rotatable upon a pin 37, and the third arm 38 has a screw 39, which travels in a slot 40 in an arm 41 (Fig. 6) the one end of which is linked, by means 110

of a screw 42, with the hook arm 43 mounted upon a pin 44. This arm has a hook or nose 45 which coöperates with a pin 46 on the rear side of the disk 20, the arm 43 being acted upon by a spring 47.

On the end of the arm 35 is a hook 49 rotatable around a pin 48, which hook is kept in the position shown on Fig. 1 by a small spring 50, and the lever 34, 35 itself is influenced by a small spring 51 (Fig. 3).

On the arm 32 is a finger 52 (Figs. 1 and 3) which coöperates with the one end of a two armed lever 53, 54 rotatable upon a spindle 60, and the bent end 55 of the upper lever arm 54 enters into a notch 56 in the coin chute 7. The arm is kept in the position shown in Fig. 2 by a small spring 57.

Normally all the movable parts occupy the position shown in Fig. 1. The bent end 10 of the upper arm 12 of the three armed lever 12, 13, 14 retains the coin introduced in the coin chute 7, and the arm 13 presses on the arm 17 so that the stop 3 is lifted from the balance 2. The hook 49 has caught the bend 11, so that the arm 34, 35, 38 occupies the position shown in Fig. 1 by which the two cover plates 25 and 26 are swung out in the open position. The wheel 21 with the disk 20 is turned slowly by the clockwork, in the same direction as the hands, so that the disk 20 makes one revolution, for instance, in 24 hours, and the bend 18 of the arm 14 is held in engagement with the rim of the disk 20 by the tension of the spring 6.

During the turning of the member 21 the pin 46 will gradually press against the nose 45 on the link 43 (Fig. 6) and thereby displace this lever system to the left, the screw 39 sliding in the slot 40. During the continued turning of the disk, the edge 58 (Fig. 1) of the small plate 23 engages the bend 18 on the arm 14, and thereby uncovers the notch 19. When this is turned to such an extent that the bend 18 may slip into the notch 19, the lever 12, 13, 14 will upon the bend 18 entering the notch be turned, owing to the spring 6 tending to lift the arm 13. Thereby the arm 12 will turn to the position shown in Fig. 2 and release the coin, which will fall vertically down through the coin chute and by its fall strike against the bent end 11, which by the swinging of the arm 14 is projected into the coin chute. By the impact of the coin with the bend, this will be pushed back to the initial position, so that the forward and backward turning of the lever 12, 13, 14 will take place in the course of a very short time, for instance a second. By the swinging of the arm 14, the hook 49, 60 has, however, been released, whereupon the spring 51 will turn the lever 34, 35, 38, and swing the cover plates 25 and 26 to the closing position.

As soon as the coin in falling has moved 65 the bend 11 (Fig. 1) to the left, the bend 18

will be disengaged from the notch 19, and the cover plate 23 will then instantly be turned back to the initial position by the spring 24, and prevent the lever 12, 13, 14 from turning back again.

The two cover plates 25 and 26 will however not immediately return to their original position, but will remain in the closed position until the pin 46 has turned so far, that it may slip behind the nose 45. The link 43 and the arm 41 will then move to the right (Fig. 6) operated on by the spring 47, and by the operation of the screw 39 on the arm 38 the three-armed lever 34, 35, 38 turns back to the position shown on Fig. 1.

By determining the position of the pin 46, the length of time, the cover plates shall be down, may be predetermined.

When it is perceived from the dial being covered that a fresh coin has to be inserted and that possibly the clock also requires rewinding, the introduction of a fresh coin in the coin chute of the clock will turn the two-armed lever 53, 54 around the pin 60, as the coin in order to get into the coin chute 90 presses the bent end 55 of the arm 54 out the notch 56. Thereby the arm 53, which coöperates with a finger 52 (Figs. 1 and 2) on the crank lever 32 turns the said lever and thereby the two cover plates back to 95 the open position.

If, however, the owner of the clock is unaware that the clock dial is covered and accordingly omits to insert a fresh coin, the covering plates will in the manner described 100 after the expiration of a time again go back to the normal position, and the clockwork will again run for another period, for instance, 24 hours. Then the notch 19 of the disk 20 will again be uncovered, and the 105 bend 18 will again engage therewith, but as there is now no coin in the coin chute, which by its fall may turn the arm 14 and thereby again swing the bend out from the notch 19, it will remain engaged and the arm 13 being 110 raised, releases the finger 17, whereupon the stop 3 will turn down against the balance 2 and stop the escapement of the clock at the same time that the closing plates again come together and cover the dial.

By inserting a fresh coin in the coin chute, it will by its fall strike the bend 18 aside and thereby turn the arm 14, so that the stop 3 again releases the clockwork.

In Figs. 7 and 8 are shown two modified forms of the cover disk for the clock dial. In Fig. 7 this disk is shown arranged as an iris diaphragm, which is turned by the link 33, and in Fig. 8 is shown a disk with radial projections, which normally cover the intervals between the hour-numerals of the clock dial, but which by a small turning movement caused by the arms 33 and 36 is turned $\frac{1}{2}$ of a revolution, thereby covering the numerals.

What I claim and desire to secure by Letters Patent, is:

1. In a savings clock adapted to be kept running by the periodical insertion of a coin, the combination with a coin chute, a balance wheel, and a stop for said wheel, of a disk provided with a slot and operated by the clock work, a spring operated plate normally covering the slot of the disk, and a three armed lever, two of the arms having members projecting into the coin chute and one of the said two arms having a second member adapted to engage the said plate to uncover the slot of the disk and then to enter the slot of the disk, the third arm of the lever being adapted to engage the stop of the balance wheel to disengage it from said wheel. 10
2. In a savings clock adapted to be kept running by the periodical insertion of a coin, cover plates for the dial of the clock, means controlled by the clockwork for operating the cover plates and including a coin controlled lever, and means operated by said lever for controlling the clockwork. 20
3. In a savings clock adapted to be kept running by the periodical insertion of a coin, a coin controlled lever having a projecting member at its lower end, pivoted cover plates for the clock dial provided with crank arms, a spring actuated armed lever, links connecting the arms of the said lever with the crank arms of the cover plates, a notched disk carried by the clockwork, a spring actuated member normally overlying the notch of the disk and adapted to be moved from over the same by the member of the coin controlled lever to allow the member to enter the notch, and a hook carried by one arm of the said lever for engaging the coin controlled lever, said hook being adapted to be disengaged from the coin controlled lever when the latter is operated. 30
4. In a savings clock adapted to be kept running by the periodical insertion of a coin, a coin controlled and clockwork controlling lever, means operated by the clockwork for controlling the movement of said lever, pivoted cover plates for the clock dial provided with crank arms, a spring actuated three armed lever, links connecting two of the arms of the lever with the crank arms of the cover plates, a hook carried by one of the arms of the said lever and adapted to engage the coin controlled and clockwork 55 controlling lever, an arm slidably mounted on the third arm of the three armed lever, a pivoted and spring actuated link to which the slidable arm is pivoted, said link being provided with a nose, and a revoluble member of the clock work having a pin adapted to engage the nose of the link to open the cover plates and to restore the hook to engaging position. 60
5. In a savings clock adapted to be kept running by the periodical insertion of a coin, a coin chute, a coin controlled lever, pivoted cover plates for the clock dial, said plates having crank arms, one of which carries a finger, means for operating the plates 65 from the coin controlled lever, a two armed lever adapted to be operated by the finger on the said crank arm, one arm of the lever having a member projecting into the coin chute and adapted to be operated by a coin, 70 whereby the cover plates will be turned to open position. 75
6. In a savings clock adapted to be kept running by the periodical insertion of a coin, a coin chute, a coin controlled lever, pivoted 80 cover plates for obscuring the clock dial, means for operating the cover plates from the coin controlled lever to move them over the dial, a member projecting into the coin chute and adapted to be operated by the 85 insertion of a coin in the chute, and means for operating the cover plates from said member to return them to open position. 90
7. In a savings clock adapted to be kept running by the periodical insertion of a coin, a shutter for the clock dial, and coin controlled means for periodically moving the shutter over the dial to obscure the same to remind the owner that it is time to insert another coin. 95
8. In a savings clock adapted to be kept running by the periodical insertion of a coin, stopping means for the clock, a shutter for the clock dial, and coin controlled means for operating the stopping means to 100 stop the clock and to move the shutter over the dial to obscure the same.

Signed by me at Copenhagen, Denmark,
this 16th day of May, 1917.

AAGE GEORG PETER WIINGAARD.

Witnesses:

CHARLES DUDR,
I. KNUDSEN.
